UNITED STATES PATENT OFFICE.

RICHARD E. OBERST, OF MILWAUKEE, WISCONSIN.

INCINERATING-CHIMNEY.

1,321,239.

Specification of Letters Patent. Patented Nov. 11, 1919.

Application filed May 21, 1918. Serial No. 237,441.

To all whom it may concern:

Be it known that I, RICHARD E. OBERST, a citizen of the United States, residing at Milwaukee, county of Milwaukee, and State of Wisconsin, have invented new and useful Improvements in Incinerating-Chimneys, of which the following is a specification.

My invention relates to improvements in incinerating chimneys, and pertains especially to that type of refuse burner which is combined with the chimney of an ordinary heating plant, and provided with means whereby refuse, including paper, garbage, etc., may be deposited in the fire pot from various floor levels of apartment buildings, flats, residences and other buildings wherein incinerating devices may be found useful, through hopper openings provided in the chimney for that purpose. One object of my invention is to provide a grating adapted for use in the enlarged lower end of the refuse burning chimney, and which will not become clogged with garbage in such a manner as to check the air currents normally moving upwardly in the chimney, these air currents being utilized to dry the garbage. A further object of my invention is to provide a grating having a raised portion terminating in an oblique extension which will not only prevent the chimney currents from being obstructed by the garbage, but which will also receive the impacts of the falling garbage, and break open the packages thereof, it being common practice for the householder to wrap up refuse material in papers before dumping it into the incinerating chimney.

A further object of my invention is to provide means for preventing burning materials from being carried upwardly by the air currents to the top of the chimney where such materials might otherwise be deposited upon the roof of the building, or upon the roofs of adjacent buildings. A further object is to provide a chimney of the described class in which the structural features are reduced to the simplest possible form, while affording maximum strength at minimum cost.

50 In the drawings:

Figure 1 is a vertical sectional view of a chimney embodying my invention.

Fig. 2 is a similar view, taken at right angles, to Fig. 1.

65 Like parts are identified by the same reference characters throughout both views.

The chimney A is enlarged at its lower end on three sides, three of the walls of the chimney being inclined as indicated at B and B' in Figs. 1 and 2. C is the smoke pipe of a heater located in the basement of a building, and below this smoke pipe the chimney is provided with a fuel opening D and an ash pit opening D', these being closed by hinged doors E and E' respectively. 65

Within the enlarged lower portion of the chimney a grate supporting frame F is mounted, and a tilting grate G is pivoted in this frame upon a transverse axis, one of the pivotally supported trunnions G' being 70 extended through the chimney wall, and provided with an exterior handle H, whereby the grate may be oscillated.

It will be observed that the grate supporting frame does not extend entirely across the fire pot cavity of the chimney, but terminates at a distance from the rear wall. The rear portion of the grate G is provided with a vertical extension J, having at its upper end an inclined extension J', the upper margin of which bears against the rear wall of the chimney at K when the grate G is in normal horizontally disposed position. The extensions J and J' are rigidly connected with the grate G, whereby, when the latter is 85 tilted by means of the handle H to the position indicated by dotted lines in Fig. 2, the extensions J and J' will be lifted and swung forwardly as also indicated by dotted lines. The inclined portion J' may thus be swung 90 to or beyond a position in which its bars are vertically disposed.

It will be observed in Fig. 1 that the extensions J and J' comprise a series of parallel upwardly extending bars, substantially half elbowed at an intermediate point, as indicated at K', in order to provide the inclination of the portion J', whereby the space between the vertical portion J and the rear wall of the chimney may be sufficiently inclosed to prevent garbage from passing downwardly at the rear of the horizontal grate G to the bottom of the ash pit L. 95

The portion M of the chimney above the 105 grate G and below the feed opening D constitutes the fire pot portion of the chimney. The garbage may be dropped on the grate from various floor levels through hopper openings N provided with gravity operated 110 lids O. Above these hopper openings I preferably locate a pivoted screen P, hav-

ing centrally disposed transversely extending trunnions journaled in the chimney walls, and extended on one side to the exterior, where one of the trunnions is provided with a weighted handle Q adapted to hold the screen P normally in a horizontal position. The screen P may be located above the uppermost hopper opening, although this is not essential, since any garbage, dumped upon the screen from a level above that occupied by the screen, may readily be allowed to fall to the bottom of the chimney by lifting the weight Q, and swinging the weight supporting lever toward a horizontal position. As soon as the weight is released it will automatically swing downwardly by gravity, and restore the screen to a horizontal position. The screen may be a perforate sheet metal screen, or it may be composed of wire netting, or of a set of grate bars.

In use, the garbage will be dumped upon the grate G from the various floor levels through the hoppers N. Most of the garbage will strike the inclined portion J' of the grate, and will be distributed from this portion to the horizontal portion G. Any packages of garbage dropped upon the grate bars J' will be broken open if in sufficient quantity and of sufficient weight to make it desirable that the contents of such packages should be distributed. If the screen P is located below the uppermost hopper, it will, of course, be necessary to oscillate it frequently in order to dump any garbage thereon, and allow the same to fall into the fire pot portion of the chimney.

The contents of the fire pot portion of the chimney may be periodically ignited. Ordinarily, the ascending air current will have dried the garbage to such an extent that paper and other material of a highly inflammable character may readily be ignited, and combustion promoted to such an extent as to completely consume the mass, but if additional fuel is required this can be inserted through the feed opening D. After the

garbage and other refuse have been consumed, the ashes and any incombustible material may be removed from the ash pit L after oscillating the grate G to dump the unconsumed material into the ash pit.

I claim:

1. The combination with an incinerating chimney, having a garbage receiving opening in its upper portion, and a grate in its lower portion, said grate comprising a fuel supporting portion, and bars extending vertically from the fuel supporting portion for part of their length, and inclined throughout the remainder of their length, and arranged with the inclined portions spanning the space between the vertical portions, and one wall of the chimney, and adapted to break up packages of material drooping from the upper opening, and to distribute the contents over the fuel on the fuel supporting portion of the grate.

2. The combination with an incinerating chimney, having a garbage receiving opening in its upper portion, and a tilting grate in its lower portion, said grate comprising a fuel supporting portion, and bars extending vertically from the fuel supporting portion for part of their length, and inclined throughout the remainder of their length, and arranged with the inclined portions spanning the space between the vertical portions and one wall of the chimney, and adapted to break up packages of material dropping from the upper opening, and to distribute the contents over the fuel on the fuel supporting portion of the grate, and means for tilting said grate in a direction to carry the vertical bars and the inclined portions thereof toward the opposite side of the chimney from that to which the inclined portions normally extend.

In testimony whereof I affix my signature in the presence of two witnesses.

RICHARD E. OBERST.
